UNITED STATES PATENT OFFICE

148,318

DESIGN FOR A HEATER OR SIMILAR ARTICLE

Luke O. Morin, Jr., and Stanley Warner, Lookout Mountain, Tenn., assignors to Chattanooga Implement & Manufacturing Co., Chattanooga, Tenn., a corporation of Tennessee

Application June 6, 1946, Serial No. 130,468

Term of patent 7 years

(Cl. D81—10)

To all whom it may concern:

Be it known that I, Luke O. Morin, Jr., a citizen of the United States, residing at Lookout Mountain, in the county of Hamilton and State of Tennessee, and Stanley Warner, a citizen of the United States, residing at Lookout Mountain, in the county of Hamilton and State of Tennessee, have invented a new, original, and ornamental Design for a Heater or Similar Article, of which the following is a specification, reference being had to the accompanying drawing, forming part thereof.

Figure 1 is a front elevation of the heater or similar article embodying our new design.

Figure 2 is a side elevation looking from the right of Figure 1.

Figure 3 is a perspective view of our heater.

We claim:

The ornamental design for a heater or similar article, as shown.

LUKE O. MORIN, JR.
STANLEY WARNER.
